UNITED STATES PATENT OFFICE.

LOUIS B. NEWELL, OF BALTIMORE, MARYLAND, ASSIGNOR TO CARR-LOWREY GLASS CO., OF BALTIMORE, MARYLAND.

DESIGN FOR A JAR.

Application filed January 7, 1922. Serial No. 99. Term of patent 7 years.

To all whom it may concern:

Be it known that I, LOUIS B. NEWELL, a citizen of the United States, residing at Baltimore, in the county of Baltimore and State of Maryland, have invented a new, original, and ornamental Design for Jars, of which the following is a specification, reference being had to the accompanying drawing, forming part thereof.

Figure 1 is a side elevation of a jar, showing my new design.

Figure 2 is a top plan view thereof.

I claim:

The ornamental design for a jar, as shown.

LOUIS B. NEWELL.
